UNITED STATES PATENT OFFICE.

REUBEN AUGUSTUS OAKLEY, OF MONTREAL, CANADA, ASSIGNOR OF ONE-HALF TO VICTOR GUERTIN, OF MONTREAL, CANADA.

FILE-BINDER.

SPECIFICATION forming part of Letters Patent No. 772,430, dated October 18, 1904.

Application filed August 24, 1903. Serial No. 170,606. (No model.)

To all whom it may concern:

Be it known that I, REUBEN AUGUSTUS OAKLEY, of the city of Montreal, in the district of Montreal and Province of Quebec, Canada, 5 have invented certain new and useful Improvements in File-Binders; and I do hereby declare that the following is a full, clear, and exact description of the same.

My invention relates particularly to the 10 means for locking the cover of a binder in different positions relatively to the base thereof according to the amount of paper or documents filed; and it has for its object to provide an easily-manipulated lock adapted to 15 effectively engage smooth standards.

To this end the invention may be said, briefly, to consist of a carrying-bar having a pair of perforations to enable it to be slid up and down a pair of standards carried by the base of the 20 binder. A pair of levers are pivoted to the bar near the perforations therein and are adapted to be moved to have one end of each intersect the space inclosed by said perforations, thereby engaging the standards projecting 25 therethrough, in which engaging positions they are held by their own natural resiliency with the coaction of a device for moving such levers. This device is located in the center of the bar and is manipulated with a key, which 30 is temporarily held to the bar while the latter is unlocked from engagement with the standards, thereby allowing the bar to be raised or lowered by the key.

For full comprehension, however, of my invention reference must be had to the accompanying drawings, forming a part of this specification, in which similar reference characters indicate the same parts, and wherein—

Figure 1 is a perspective view of a portion 40 of the binder provided with my invention. Fig. 2 is a plan view of the carrying-bar removed and illustrating particularly my improved levers in their unlocked position. Fig. 3 is a similar view illustrating the levers in 45 their locked position. Fig. 4 is a detail view of the key. Fig. 5 is a vertical sectional view taken on line A A, Fig. 2, and illustrating particularly the manner in which the key and bar are connected together while the levers

are unlocked from the standards to enable 50 the bar to be lifted by the key; and Fig. 6 is a transverse vertical sectional view taken on line B B, Fig. 3, and illustrating the parts in locking position with the key released.

The bar *b* has a pair of perforations *c* there- 55 in which enables it to be slid upon a pair of standards *d*, carried rigidly by the base *e* of the binder. These standards are perfectly smooth, but otherwise of usual construction and secured to the base of the binder in the 60 usual way.

My improved levers are of **U** form, and each has one leg *f* elongated to constitute a lever-arm, while its other leg, *g*, is short to insure rigidity, while such levers are ful- 65 crumed to the bar, as at *h*, in positions to have their short arms adapted to move into intersection with the standards. These levers are moved into engagement with the standards by having their elongated legs projecting to- 70 ward one another and overlapping at their ends, a cam-block *m* being pivoted to the center of the bar between the ends of these legs and having a central circular boss *n*, slotted, as at *o*, and a pair of holes *p*, located one at 75 each side of said boss and in line with said slot. This cam-block is of oblong form, with its corners slightly rounded and its ends flat to provide an extended bearing-surface for holding the levers in their engaging positions. 80 This bar, with the levers and cam-blocks thereon, is inclosed in a shell *r*, preferably of sheet metal, and having a circular center opening into which the circular boss of the cam-block projects and a pair of radial slots *s*, ex- 85 tending transversely of the bar, while a pair of perforations *t* register with the perforations in the bar and, like the latter, accommodate the standards, such shell being connected to the bar by having its side and end 90 edges drawn down over those of the bar and a series of lugs *u* bent beneath same. The lock thus constructed may be secured to the cover *v* of the file by screws *w* or otherwise, as desired. The key *x*, whereby the lock is 95 manipulated, has a pair of teats *2*, adapted to project into the holes in the cam-block, and a straight portion between said teats adapted to

take into the slot in the boss of said cam-block, while a pair of opposite notches 4 above and in close proximity to the teats receive the edges of the circular opening of the shell when 5 the key is turned to its unlocking position, thereby enabling the shell and the lock-carrying bar therein to be raised or lowered by the key.

Although I have described the construction 10 as having a bar upon which the levers are mounted and such bar connected to the cover, it is obvious that, if desired, a cover of sufficient strength to support the locking part may be used and such parts mounted directly 15 thereon, thereby dispensing with the bar, without departing from the spirit of my invention. In fact, the bar constitutes a strengthening part of the cover and is to all intents and purposes an integral part of the 20 cover.

What I claim is as follows:

1. In a file-binder, a cover, a shell covering the top of said cover, means readily removable from such cover and for locking the same 25 in different positions according to the amount of papers or documents filed, said means being adapted to be inserted between the shell and cover midway of the length and breadth of the latter for the purpose of raising and lowering said cover to different positions.

2. In a file-binder, a base, a pair of standards carried by said base, a cover, a shell covering the top of said cover, said shell and cover being perforated to allow the standards 35 to project therethrough, locking devices located between said cover and shell and whereby the cover is locked to said standards, said shell having a keyhole therein, and a key adapted to be inserted into said keyhole and 40 whereby the locking devices are operated, such key having engaging devices thereon for engaging the shell when the locking devices are unlocked for the purpose of enabling the cover to be lifted.

45 3. In a file-binder, the combination with the base thereof having a pair of standards, and a cover perforated to fit over said standards and adapted to be moved up and down thereon, of means for locking the cover in any position 50 to which it may be moved upon said standards, such means consisting of a pair of levers of U form fulcrumed to said cover adjacent to the perforations through which the standards project each of said levers having one arm resilient and the other arm adapted to intersect the perforations in the cover, and means for bearing upon the resilient arm of each lever and moving said levers to cause the end portion of one of the arms of each thereof to engage 55 one of said standards and secure said cover against movement relatively to said standards.

4. In a file-binder, the combination with the base thereof having a pair of standards, and a 60 cover perforated to fit over said standards and

adapted to be moved up and down thereon, of means for locking the cover in any position to which it may be moved upon said standards, such means consisting of a pair of levers of U form fulcrumed to said cover adjacent to 70 said perforations, each of said levers having one leg resilient and elongated, and their elongated legs projecting toward one another and having their ends overlapping, the other legs of such levers being short and adapted 75 when the levers are moved to intersect such perforations and engage the standards projecting therethrough, and means located between the overlapping ends of said elongated legs whereby said levers are moved to bring 80 their short legs into engagement with the standards, substantially as described and for the purpose set forth.

5. In a file-binder, the combination with the base thereof having a pair of standards, and a 85 cover perforated to fit over said standards and adapted to be moved up and down thereon, of means for locking the cover in any position to which it may be moved upon said standards, such means consisting of a pair of levers of 90 U form fulcrumed to said cover adjacent to said perforations, each of said levers having one leg resilient and elongated, and their elongated legs projecting toward one another and having their ends overlapping, the other 95 legs of such levers being short and adapted when the levers are moved to intersect such perforations and engage the standards projecting therethrough, a cam-block pivoted between said overlapping ends and adapted 100 when moved to one position to separate said elongated legs and when moved in the opposite direction to release same, and a key whereby said cam-block is rotated.

6. In a file-binder, the combination with the base thereof having a pair of standards and a cover perforated to fit over said standards and adapted to be moved up and down thereon, of means for locking the cover in any position to which it may be moved upon said standards, such means consisting of a pair of levers of 105 U form fulcrumed to said cover adjacent to said perforations, each of said levers having one leg elongated, and their elongated legs projecting toward one another and having 110 their ends overlapping, the other legs of such levers being short and adapted when the levers are moved to intersect such perforations and engage the standards projecting therethrough, an oblong cam-block having its corners round and its ends flat, such cam-block being pivoted between said overlapping ends and adapted when moved to one position to separate said elongated legs and when moved 115 in the opposite direction to release same, and a key whereby said cam-block is rotated.

7. In a file-binder, the combination with the base thereof having a pair of standards and a cover perforated to fit over said standards and adapted to be moved up and down thereon, of 130

- means for locking the cover in any position to which it may be moved upon said standards, such means consisting of a pair of levers of **U** form fulcrumed to said cover adjacent to said 5 perforations, each of said levers having one leg resilient and elongated, and their elongated legs projecting toward one another and having their ends overlapping, the other legs of such levers being short and adapted when the levers are moved to intersect such perforations and engage the standards projecting therethrough, an oblong cam-block having its corners round and its ends flat, such cam-block being pivoted between said overlapping 10 ends and adapted when moved to one position to separate said elongated legs and when moved in the opposite direction to release same, and a key whereby said cam-block is rotated.
8. In a file-binder, the combination with the base thereof having a pair of standards, a bar 15 perforated to fit over said standards and adapted to be moved up and down thereon, a shell inclosing the upper side of said bar and having a central circular opening with radial slots, 20 a cover secured to the under side of said bar, of means for locking the cover in any position to which it may be moved upon said standards, such means consisting of a pair of levers 25

of **U** form fulcrumed to said cover adjacent to said perforations, each of said levers having one leg elongated, and their elongated legs projecting toward one another and having their ends overlapping, the other legs of such levers being short and adapted when the levers are moved to intersect such perforations and engage the standards projecting therethrough, an oblong cam-block having its corners round and its ends flat and provided with a slotted boss projecting through the central openings in the shell and having a 30 pair of holes one at each side of said boss pivoted between said overlapping ends and adapted when moved to one position to separate said elongated legs and when moved in the opposite direction to release same, and a key having longitudinal teats adapted to take 35 into the holes in the cam-block and a straight portion between said teats to engage in the slot in the boss whereby said cam-block is rotated.

In testimony whereof I have affixed my signature in presence of two witnesses. 40
